GEORGE A. GIESELER, OF CLEVELAND, OHIO.

NEUMATIC CONVEYING MECHANISM.

1,369,648.

Specification of Letters Patent. Patented Feb. 22, 1921.

Application filed January 2, 1920. Serial No. 348,854.

To all whom it may concern:

Be it known that I, GEORGE A. GIESELER, a citizen of Germany, residing at Cleveland, Ohio, have invented certain new and useful 5 Improvements in Pneumatic Conveying Mechanisms, of which the following is a specification.

The invention relates particularly to mechanism for pneumatically conveying 10 powdered or pulverized or granular material. Such mechanism frequently includes a flexible pipe or hose at the end of which is a nozzle which is placed on or in the material to be conveyed. The material is drawn into 15 the nozzle and through the pipe. Frequently a plurality of such flexible receiving pipes are used in a single installation. When the distance the material is to be conveyed is not great it is possible, and sometimes convenient, to continue each receiving 20 pipe to the place of deposit. Frequently, however, it is desirable and economical to attach a plurality of receiving pipes to a single delivery pipe through which the material 25 may be delivered to the point of deposit. Suction is applied so as to tend to create a vacuum in the pipes and so draw the material to be conveyed through the receiving pipe and into and through the delivery pipe. 30 Where a plurality of streams of material come together at the point where the receiving pipes unite into the delivery pipe there is liability of a blockade or jamming of the material. More or less hard lumps may get 35 caught at this point and be packed in tightly or with finer material. This has sometimes necessitated shutting down the pump creating the vacuum and disassembling the apparatus to remove the material blocking the 40 passage. One result of this has been that it has frequently seemed economical to install long stretches of individual delivery pipes for each individual receiving pipe rather than contemplate the delays and expensive operation necessary to clean away 45 the frequently occurring blockades incident to the use of a single delivery pipe with a plurality of receiving pipes.

It is a purpose of my invention to provide 50 a system involving a single delivery pipe supplied with a plurality of receiving pipes which will not have the disadvantages above set out.

One form the invention may take is indicated in the accompanying drawings in which Figure 1 is a front elevation of a

joint between a delivery pipe and a plurality of receiving pipes made in accordance with the invention; Fig. 2 is a transverse vertical section of a relieving valve and Fig. 3 is a 60 top plan view of the relieving valve.

A delivery pipe 1 is preferably made of metal and rigidly held in place. Only the end of this pipe is shown but it will be understood that it will extend any suitable 65 distance to the point of deposit or storage of the conveyed material. Entering the delivery pipe two receiving pipes 2 are shown each provided with flexible hose portions 3 which are provided at their ends with nozzles (not shown) of any suitable form to be placed in or on the material to be conveyed. In an extension 4 of the delivery pipe 1 is a valve chamber 5 having within it a partial diaphragm 6 through which extends the 70 stem 7 of a valve 8. The stem 7 is provided with a nut 9 to hold it from passing through the hole in the partial diaphragm and also to adjust the distance between the valve 8 and the valve seat 10 which is formed at the 75 lower end of the valve chamber 5. The valve stem 7 is prolonged beyond the valve 8 and carries a plurality of weights 11. The number and weight of the blocks 11 may be varied at will to adapt the valve for 80 different conditions of operation. A nut 12 is shown to hold the weights 11 in place on the valve stem 7. When the apparatus is not in use the weights hold the nut 9 close 85 against the partial diaphragm 6 thereby causing the valve 8 to stay away from the valve seat 10. This position is shown in Fig. 2. In operation a partial vacuum is created in the delivery pipe 1 thereby causing material to be sucked up through the 90 receiving pipes 3. The vacuum thus created is normally sufficient to overcome the weights 11 and cause the valve 8 to be closed against its seat 10. The material from the receiving pipes 3 enters the delivery pipe 1 95 frequently in great quantities and at high speed. Frequently the material because in lumps or for other reasons arranges itself in such a way as to jam or block that pipe, and thus the passage of material may be impeded or stopped. At this time the vacuum in the extension 4 of the delivery pipe 1 will decrease and will finally reach a point at which the weights 11 will overcome the suction and consequently force the valve 8 to open automatically from its seat 10. This will allow 100 air at atmospheric pressure to enter the de- 105

livery pipe 1 at its point of junction with the extensions 2 of the receiving pipes 3. The pressure thus exerted automatically on the materials blocking the pipes will be sufficient to force the jammed material through the delivery pipe 1 thus setting the apparatus into normal action again at which time the renewed vacuum in the extension 4 will cause the valve 8 to close against its seat 10 until another block occurs or the operation of the apparatus is discontinued. It is thus possible to employ a plurality of receiving pipes for quickly conveying a large quantity of material in conjunction with a single delivery pipe and insure continuous efficient working of a relatively cheap installation.

The details of the mechanism shown and described are illustrative but are not essential to the invention.

20 I claim as my invention:

1. In pneumatic conveying mechanism, a delivery pipe, a plurality of receiving pipes entering the delivery pipe, and automatic means for relieving a block in the pipes.

25 2. In pneumatic conveying mechanism, a delivery pipe, receiving pipes entering the delivery pipe, and automatic relieving mechanism at the junction of the pipes.

3. In pneumatic conveying mechanism, a delivery pipe, receiving pipes entering the 30 delivery pipe, and automatic means for admitting atmospheric air at the junction of the pipes.

4. In pneumatic conveying mechanism, a delivery pipe, receiving pipes meeting the 35 delivery pipe at an angle, a relief pipe between the receiving pipes, an air valve in the relief pipe and means on the valve to cause it to open when the conveyed material blocks in the junction of the receiving and delivery 40 pipes.

5. In pneumatic conveying mechanism, a delivery pipe, receiving pipes meeting the delivery pipe at an angle, a relief pipe between the receiving pipes, an air valve in the 45 relief pipe, and weights on the valve to cause it to open when the conveyed material blocks in the junction of the receiving and delivery pipes.

6. In pneumatic conveying mechanism, a 50 delivery pipe, receiving pipes meeting the delivery pipe at an angle, an air valve at the junction of the receiving and delivery pipes, and weights on the valve to cause it to open when the conveyed material blocks. 55

GEO. A. GIESELER.
